Attorney

UNITED STATES PATENT OFFICE.

JOSEF SCHOLZ, OF BASIN, WYOMING.

ICE-CUTTING MACHINE.

1,330,907.

Specification of Letters Patent.

Patented Feb. 17, 1920.

Application filed November 2, 1917. Serial No. 199,860.

To all whom it may concern:

Be it known that I, JOSEF SCHOLZ, a citizen of the United States, and resident of Basin, in the county of Bighorn and State 5 of Wyoming, have invented certain new and useful Improvements in Ice-Cutting Machines, of which the following is a specification.

This invention has reference generally to 10 improvements in sawing machines and more particularly relates to an ice cutting machine.

The invention has for its principal object 15 to provide a machine of the above mentioned character adapted to be disposed across a channel in an ice field for cutting into cakes a strip of ice which is floatingly supported in the channel.

Another object of the invention is to provide 20 an ice cutting machine of this character, which is formed with a stationary supporting frame, carrying a drive shaft, and a swinging frame on the lower end of which is mounted a circular saw operatively connected with the drive shaft, said swinging frame being manually movable across the channel to cut the strip of ice therein, into cakes.

Still a further object of the invention is to 30 provide an ice cutting machine of the character described which is provided with a gage whereby the length of the cake cut is regulated, said gage being adjustable by means of a pivoted lever disposed within 35 easy reach of the operator of the machine.

Still a further object of the invention is to 40 provide a device of this character, which is easily and simply constructed, inexpensive to manufacture, and one which will be very efficient in operation.

With these and numerous other objects in view, my invention consists of the novel features of construction, combination, and arrangement of parts, which will be herein referred to and more particularly pointed out 45 in the specification and claims.

In the accompanying drawings:

Figure 1 is a side elevation of the machine;

Fig. 2 is an end view of the same, with the protecting covers broken away;

Fig. 3 is a vertical transverse section through the machine;

Fig. 4 is a detail perspective view of the

lower end of the adjustable swinging frame; 55 and

Fig. 5 is a horizontal section on the line 5—5 of Fig. 4.

In describing my invention, I shall refer 60 to the drawings in which similar reference characters designate corresponding parts throughout the several views.

The ice cutting machine comprises a stationary supporting frame, which is formed 65 of a pair of parallel spaced V-shaped standards 1, which are provided with transverse cross strips 2, the base strips 3 projecting beyond the standards 1, and having additional fastening means 4, for securing the same to the upper surface of the ice on opposite sides of a channel 3' which is cut through the ice and in which is adapted to be floatably supported a strip of ice 4'. The two spaced standards 1 are connected by 70 connecting bars 5, disposed adjacent the apex, and bases of the same.

Carried by the main supporting frame, is a rotatably mounted drive shaft 6, which is mounted in bearings 7 supported adjacent the apex of the standards as shown at 8, and 80 said drive shaft has mounted thereon near one end, which projects from one of the side standards 1, a pulley 9, which has trained thereover a drive belt 10, that is connected with some suitable source of driving power. 85 The pulley is provided with a clutch 11, operable by a lever 12, which is pivotally mounted on the adjacent side standard 1, and has its lower end disposed adjacent one side of the machine, within easy reach of the 90 operator. Between the side standards 1, is mounted a fly wheel 13 on the drive shaft 6.

The clutch 11 includes an annular channel to receive the lever 12 when the latter swings upon its pivot, and the pivot is capable of 95 permitting the lever to swing in two directions, as shown, so that after it has been turned in one direction on its pivot to dispose the lever within the annular channel of the clutch, the lower end of the lever is 100 moved outwardly to cause the slidable portion of the clutch to be moved inwardly, or toward the pulley 9, to close the clutch. When not in use the lever 12 hangs idly.

A swinging frame 14 which is formed of 105 pairs of parallel side bars 15, is mounted between the side standards 1, and is loosely carried by the drive shaft 6, by bearing

members 16 positioned adjacent the upper extremities of the bars of said frame. Each of the bars 15 is formed of two slidably connected sections, so that the frame will be extensible. The frame is adapted to be held in various positions, by means of cross bars 17 which extend between the side bars 15 as clearly shown in Fig. 4 of the drawings, and having loops formed at their opposite ends 10 surrounding the adjacent bars 15, and provided with set screws 18, to lock said bars in various longitudinally adjusted positions. This adjustment however is very slight, it being merely necessary to adjust the swinging frame 14 to a very slight degree. The drive shaft 6 has a sprocket wheel 19 mounted thereon between the side bars 15 of the swinging frame 14, for a purpose to be hereinafter more fully described.

20 On the lower extremities of the side bars 15 of the frame 14, are alining bearing members 20, through which is mounted a driven shaft 21, carrying a sprocket wheel 22 between the bars of the frame, and the sprocket 25 wheel 22, and sprocket 19 on the drive shaft 6, are connected by a chain 23. The shaft 21 projects from one side of the swinging frame 14, and has mounted thereon a circular saw 24. If desired any number of 30 these saws may be employed. The swinging frame 14, is provided with a projecting handle 25, which extends through one end of the main supporting frame, and is within easy reach of the operator, so that it may be 35 grasped to move the swinging frame, and saw across the strip of ice 4' for cutting the latter into cakes.

The machine is provided with a gage 40 which regulates the length of the cake cut, which comprises an upright iron bar 26, that is slidably mounted through a bracket 27 secured to one of the cross strips 2, that supports one of the side standards 1. This strip is provided with an enlarged upper 45 end 28, and has its lower end flattened as shown at 29, said flattened lower end being connected to the inner end of an operating lever 30 projecting through one end of the frame and disposed adjacent the handle 25, 50 only at the opposite side of the machine therefrom. One end of the machine, from which the lever projects and which may be called the front of the machine, is provided with protecting covers 31 and 32 55 which are mounted on the connecting bars 5 at said end of the machine, and which prevent the operator from being splashed during the cutting operation, as well as affording a protection for the gearing at the 60 top of the machine.

The mode of operation of the present invention may be reviewed as follows:

Assuming that the machine has been constructed in the manner shown and described, 65 the machine is connected with any desired

motive power, preferably a gas engine, or electrical motor, that operates the belt 10 connected with the pulley 9. Movement of the belt, will rotate the pulley, and upon throwing of the clutch 11 into operative position, by movement of the lever 12, the drive shaft 6 will be rotated. This rotation of the shaft 6, will rotate the sprocket wheel 19, and hence the shaft 21 will be likewise rotated, owing to the connection of the same 70 to the chain 23, and sprocket 22. This movement will rotate the circular saw 24, which may be guided into engagement with the ice by the handle 25, which regulates the movement of the swinging frame 14. This 75 frame 14 is mounted to act as a pendulum to swing back and forth within the machine, and into engagement with the strip of ice, as clearly shown in Figs. 1 and 3 of the drawings. The circular saw will cut the 80 strip of ice 4' into cakes, it being obvious that the ice row is moved correspondingly after each cake has been cut.

Attention is directed to the fact that the operating lever for the swinging frame, the 90 control lever for the clutch and the gage lever all project from the front end of the machine and are disposed within easy reach of the operator. The swinging frame 14 is adjustable longitudinally as has been described, a slight adjustment being necessary, as is obvious, but when desired the frame may be adjusted to increase the radius of 95 the saw, by inserting a longer length chain between the sprocket wheels.

100 From the above description taken in connection with the accompanying drawings, it is thought that a clear and comprehensive understanding of the construction, operation, and advantages of my invention may 105 be had, and while I have shown and described the device as embodying a specific structure, I desire that it be understood that such changes may be made in said structure as do not depart from the spirit and scope of 110 the invention as claimed.

Having fully described my invention, what I claim as new, and desire to secure by Letters Patent, is:—

115 1. An ice cutting machine including a main stationary supporting frame adapted to be disposed across a channel in an ice field, a main shaft rotatably mounted in the frame near the upper end thereof, another frame the sides of which consist of relatively adjustable sections, cross bars arranged between the sections and designed for engagement thereabout, means co-operating with the cross bars for clamping the sections in a relatively adjusted position, 120 means for pivotally supporting the adjustable frame on the main shaft, another shaft journaled in the lower portion of the adjustable swinging frame, transmission means arranged between these shafts, a saw carried 125 130

by the last mentioned shaft, a handle connected to the swinging frame for moving said frame across the channel so that the saw will act on a strip of ice supported in 5 the channel, a gage slidably connected to the main frame for releasably holding the strip of ice and for regulating the length of the ice cake cut by the saw, and a lever swingably connected to the main frame and con- 10 nected to the gage for raising and lowering the gage.

2. An ice cutting machine including a main stationary supporting frame adapted to be disposed across a channel in an ice 15 field, a main shaft rotatably mounted in the frame, an auxiliary frame pivotally supported from the main shaft and having sides consisting of relatively adjustable sections,

cross bars arranged between the sections and designed for engagement thereabout, means 20 coöperating with the cross bars for clamping the sections in a relatively adjusted position, a saw carrying shaft journaled in the lower portion of the auxiliary frame and rotated from the main shaft, means permitting 25 said auxiliary frame to be moved across the channel so that the saw will act upon a strip of ice supported in the channel, and means connected with the main frame for releasably holding the strip of ice and for 30 regulating the length of the ice cake cut by the saw.

In testimony whereof I affix my signature hereto.

JOSEF SCHOLZ.
